ELECTROPHOTOGRAPHIC PRINTING MACHINE

William F. Dalton, Pittsford, Claude Hutcheson, Fairport,
and Ruediger W. Knodt, Rochester, N.Y., assignors to
Xerox Corporation, Stamford, Conn.

Filed July 10, 1972, Ser. No. 270,413

Term of patent 14 years

Int. Cl. D16—03

U.S. Cl. D61—1 Q

FIG. 1

FIG. 2

FIG. 3

FIG. 4

FIG. 5

FIG. 1 is a front and right side perspective view of an electrophotographic printing machine showing our new design;

FIG. 2 is a front and left side perspective view thereof;

FIG. 3 is an enlarged top plan view thereof;

FIG. 4 is an enlarged right side elevational view thereof; and

FIG. 5 is an enlarged left side elevational view thereof.

We claim:

The ornamental design for an electrophotographic printing machine, substantially as shown and described.
